UNITED STATES PATENT OFFICE.

WILLIAM E. MINNELEY, OF WELLSVILLE, NEW YORK.

HARNESS-BUCKLE.

SPECIFICATION forming part of Letters Patent No. 284,467, dated September 4, 1883.

Application filed June 21, 1883. (No model.)

To all whom it may concern:

Be it known that I, WILLIAM E. MINNELEY, of Wellsville, in the county of Allegany and State of New York, have invented an Improved Harness-Buckle; and I do hereby declare the following to be a full and exact description thereof, reference being had to the accompanying drawings, making part of this specification.

10 Figure 1 is a top view of the buckle; Fig. 2, a view of the under side of the same; Fig. 3, a side view thereof; Fig. 4, a central longitudinal section of the buckle, with a portion of a hame-tug and trace, to which it is attached.

15 Like letters designate corresponding parts in all the figures.

This invention is an improvement in lever-bail buckles.

The frame A has parallel sides *a a*, concavely 20 curved on top, so that the end bars, *b c*, may both rest upon the top of the trace, and it has two cross-bars, *d f*, across its middle, with sufficient space between them to admit the bail B. The sides of the bail rest in offset-openings *g g*, of sufficient size to admit its free play 25 therein, the bail turning on the front extremities thereof, which form fulcra for the same. These middle cross-bars form a bed, on which the under side of the trace C rests, and the lever-bail firmly draws the trace directly down 30

thereon when the hame-tug D is drawn upon. From the under side, preferably, of the front end bar, *b*, projects a tongue, *h*, to enter the tongue-holes of the trace. This holds securely in the trace when draft is on the same, the other end bar, *c*, which rests on the trace, assisting to keep the tongue in place, and when the tongue is to be shifted to another hole in the trace the space between the bar *b* and front middle bar, *d*, is sufficient to allow a free withdrawal and insertion of the tongue, while the bail, freely swinging, does not impede the manipulation of the trace. The buckle is therefore very convenient in use, as well as compact and handsome in form.

40 45 What I claim as my invention, and desire to secure by Letters Patent, is—

In a harness-buckle, a buckle-frame, A, constructed with the two end bars, *b c*, to rest upon the upper side of the trace, two middle bars, *d f*, upon which the under side of the trace bears, and a tongue, *h*, on the under side of one end bar, *b*, in combination with a lever-bail, B, working in openings *g g* between the two middle bars, for the purpose herein specified.

50 55 WILLIAM E. MINNELEY.
